UNITED STATES PATENT OFFICE

2,000,644

TENT

Frank M. Powers, Chicago, Ill., assignor of one-third to Thomas C. Powers and one-third to David W. Powers, both of Chicago, Ill.

Application August 1, 1934, Serial No. 738,004

9 Claims. (Cl. 135—1)

This invention relates to improvements in tents and especially applicable to the so-called umbrella tent with a single center pole, although it may be applied to a tent of practically any type or shape having side walls and top connected at the eaves, in which such eaves are above the top of the door.

Among the features of my invention is the provision of a frame at the eaves comprising rigid bars suitably connected together. By the use of such a frame, the desired shape of the tent is maintained and the top and walls thereof are kept straight and in proper position.

Another feature of my invention is the provision of flexible tension members connecting the middles of the rods to the top of the tent pole, whereby the rods may be kept from sagging and maintained in proper position. By the use of such tension members or guys, a relatively light material may be used for constructing the rods comprising the frame.

My improved tent is light, durable and roomy; and may be erected or taken down in a relatively short time. The inventions herein claimed increase the utility of the tent without a material increase in weight or cost of manufacture.

Other features and advantages of my invention will appear more fully as I proceed with my specification.

For the purpose of illustrating the invention, I have herein shown the same applied to a four-sided umbrella tent with a center pole, although it is obvious that the tent may have fewer or more sides.

In that form of device embodying the features of my invention shown in the accompanying drawing—

Figure 1 is a view in perspective; Fig. 2 is a top plan view of the frame and tension ropes, showing the same with the tent removed; Fig. 3 is a vertical sectional view of the upper part of the tent; and Fig. 4 is a view taken as indicated by the line 4—4 of Fig. 2.

As shown in the drawing, the tent has a square bottom and comprises four side walls connected at their upper edges, or eaves, to a pyramidal top. As here shown, the side walls slant inwardly from the bottom to the top. It is obvious that these walls may slant inwardly to any degree desired or may be vertical. The side walls are indicated by 10, 10, one of said walls being provided with a door opening 11. 12 may indicate the conventional awning over the door supported by two vertical poles 13, 13, in front of the tent.

14 indicates a pyramidal roof or top for the

tent including four triangular sheets or faces 15 with their lower edges joined to the upper edges of the side walls 10 at the eaves 15. 16 indicates the center pole for the tent.

Inside of the tent at the eaves I provide a square frame comprising four relatively stiff or rigid bars 17 joined together at their ends by bolts 18. These bars, for example, in a tent seven feet square at the bottom and about 6' 6" high at the center may be made of strap iron substantially 10 3/4" x 1/8" in cross-section. The bolts 18 extend upwardly through grommets at the corners of the tent and wing nuts 19 are applied to the bolts.

Inside of the tent, for the purpose of assisting in keeping the bars 17 straight, are provided four flexible tension members or ropes 20, each provided with a conventional tightener 21. The upper ends of the ropes are attached to a ring 22 over the pin 16^a in the top of the pole 16. One of the ropes 20 lies under and adjacent the center line of each face 14^a of the top, and the lower end of each rope carries a suitable hook 23 which engages the bar 17 near its center. The tighteners 21 are adjusted so that the bars 17 are prevented from bowing downwardly and held straight and adjacent to and in registry with the eave line 15. In a tent, as referred to above, with a seven foot square bottom, each of the bars 17 may be, for example, approximately four feet long. By using the tension members 20 to assist in holding the bars 17 in proper position, there is no sacrifice of head room by the use of objectional horizontal braces.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I claim as new, and desire to secure by Letters Patent, is:

1. A tent, including; a plurality of side walls; a top having a plurality of faces with their lower edges joined to the upper edges of the side walls; a pole for the top; a frame inside of the tent, including a bar adjacent the junction of each side wall and top face with means for connecting the ends of said bars together; and means for supporting said frame, said means including tension members extending from the top of the pole to said frame.
2. A tent as claimed in claim 1, in which the

- means for supporting the frame includes members carried by the frame and extending through the tent material and provided with fastening means outside of the tent.
5. 3. A tent as claimed in claim 1, in which the means for supporting the frame includes bolts carried by the frame and extending through the tent material and provided with nuts outside of the tent.
10. 4. A tent including; four upwardly and inwardly slanting side walls; a pyramidal top having the lower edges of its four faces attached to the upper edges of said side walls; a center pole for said top; a bar inside of the tent adjacent the junction of each side wall and top face; bolts connecting the ends of said bars, said bolts extending upwardly through the tent, and nuts outside of the tent on said bolts.
15. 5. A tent, including; four upwardly and inwardly slanting side walls; a pyramidal top having the lower edges of its four faces attached to the upper edges of said side walls; a center pole for said top; a bar inside of the tent adjacent the junction of each side wall and top face; bolts connecting the ends of said bars, said bolts extending upwardly through the tent; nuts outside of the tent on said bolts; and guy members inside of the tent extending from the top of the pole to the center portions of said bars.
20. 6. A tent, including; a plurality of side walls;

a top having a plurality of faces with their lower edges joined to the upper edges of the side walls; a pole for the top; a frame inside of the tent, including a bar adjacent the junction of each side wall and top face with means for connecting the ends of said bars together; and means for supporting said frame, said means including members extending through the tent material and provided with fastening means outside of the tent, and tension members extending from the top of 10 the pole to the center portions of the bars of the frame.

7. A tent, including; a plurality of side walls; a top having a plurality of faces with their lower edges joined to the upper edges of the side walls; 15 a pole for the top; a frame inside of the tent, including a bar adjacent the junction of each side wall and top face with means for connecting the ends of said bars together; and means for supporting said frame, said means including members adjacent the ends of the bars extending through the tent material and provided with fastening means outside of the tent, and tension members extending from the top of the pole to the center portions of the bars of the frame.

8. A tent as claimed in claim 6, in which the tension members are adjustable.

9. A tent as claimed in claim 7, in which the tension members are adjustable.
